[57] CLAIM

The ornamental design for shellfish hanger pin unit, as shown and described.

DESCRIPTION

FIG. 1 is a perspective view of a shellfish hanger pin unit;
FIG. 2 is a front view thereof;
FIG. 3 is a right side view thereof;
FIG. 4 is a left side view thereof;
FIG. 5 is a top view thereof;
FIG. 6 is a bottom view thereof;
FIG. 7 is a rear view thereof; and,
FIG. 8 is a front view of a detached shellfish pin with the broken line showing of shellfish being for illustrative purposes and forming no part of the claimed design.
One of the shellfish pins has been shown detached in FIG. 8 for clarity of illustration.
